F. F. MACLEAN.

HEADLIGHT.

APPLICATION FILED JUNE 13, 1913.

Patented Mar. 2, 1915.

UNITED STATES PATENT OFFICE.

FREDRICK F. MACLEAN, OF SYRACUSE, NEW YORK.

HEADLIGHT.

1,130,002.

Specification of Letters Patent. Patented Mar. 2, 1915.

Application filed June 13, 1913. Serial No. 773,438.

To all whom it may concern:

Be it known that I, FREDRICK F. MACLEAN, a citizen of the United States, and a resident of Syracuse, in the county of Onondaga, in the State of New York, have invented new and useful Improvements in Headlights, of which the following, taken in connection with the accompanying drawings, is a full, clear, and exact description.

10 This invention relates to certain improvements in headlights for automobiles, motor-boats and other vehicles and refers more particularly to means operable at will from the side of the vehicle for intercepting and deflecting the reflected rays of light below the direct line of vision of an approaching pedestrian, horse and drivers of other machines so as to obviate as far as possible the inconvenience, dangers and accidents resulting from the temporary blinding effect of such light and, in so far as this broad object is concerned, is somewhat similar to the devices shown in my pending applications Nos. 723,341 filed October 1, 1912 and 25 746,319 filed February 5, 1913.

Aside from the broad objects previously mentioned, the specific purpose of my present invention is to shift the movable reflector relatively to the axis of the case by means of an electric motor and suitable connections located entirely within the said case and adapted to be set in motion at will by a suitable reversing switch located within easy reaching distance from the seat of 30 the vehicle for shifting the movable reflector in reverse directions.

Another object is to provide simple means for automatically disconnecting the driving connections between the motor and movable reflector when the latter has been shifted to predetermined limits of movement in either direction and, at the same time, to allow the movable reflector to be stopped and held at any intermediate position.

45 A still further object is to provide the front of the case with a suitable door capable of being swung from either side to permit access to the lamp or reflector for adjustment or repairs.

50 Other objects and uses will be brought out in the following description.

In the drawings—Figures 1 and 2 are respectively a front elevation and a side elevation of a headlight embodying the various 55 features of my invention. Figs. 3 and 4 are respectively a longitudinal sectional

view and a horizontal sectional view taken on lines 2—2, Fig. 1, and 3—3, Fig. 2, except that a portion of the removable reflector is broken away in Fig. 4. Fig. 5 is an enlarged detail view of the motor showing the worm on the motor shaft and worm gear which it is adapted to drive and constitute a part of the means for transmitting motion to the movable reflector. Fig. 6 is an enlarged detail sectional view through one of the hinged connections between the door and case.

This reflector comprises a suitable closing case —1— of sheet metal consisting, in this instance, of a circular front section —2— and a conical rear section —3— telescoping within the rear end of the front section and locked thereto by one or more pins or screws —4— constituting a part of what is known as a bayonet lock to hold the sections in fixed relation against endwise movement when adjusted for use and at the same time permitting the rear section to be easily and quickly removed for inspection or repairs of the interior mechanism. The entire case —1—, therefore constitutes a hollow sheet metal shell of sufficient size to receive a relatively stationary reflector —5—, a movable reflector —6— and an electric motor —7— together with suitable means for transmitting motion from the electric motor to the movable reflector as will be hereinafter more fully described.

A cross bar or bracket —8— has its opposite ends permanently secured to and within the rear end of the front case section —2— while its intermediate portion projects into the front end of the rear section —3— for receiving and supporting the electric motor —7— which is attached thereto by suitable fastening means as screws —9—.

The front end of the case section —2— is somewhat larger than the corresponding end of the rear section so as to leave ample space for the reception of the relatively stationary reflector —5— together with an incandescent electric lamp —10— and a flat transparent front plate —11— and also the movable reflector —6—. The marginal edge of the glass plate —11— is mounted in a circular metal frame —12— which in turn is secured by brazing or other suitable fastening means to an annular door frame —13—, the latter being fitted in a circular opening in the front of the case section —2—. This door frame is provided with

2

diametrically opposite hinged strips or sections —14— which are connected by removable hinged pins —15— to corresponding hinged strips or sections —16— on the adjacent portions of the case section —2— so that by removing either one of the pins, the door frame together with the glass plate —11— thereon may be swung open to permit access to the lamp —10— for renewal or repairs.

10 The marginal edge of the stationary reflector —5— is secured in a circular frame —17— which in turn is rigidly secured by brazing or other fastening means to the inner face of the front of the case section —2— around the door opening and is provided with a central socket —18— in its apex for receiving an electric lamp —10—, the latter being supplied with current from 20 any suitable source through conductors —19—.

25 The movable reflector —6— is preferably made of polished sheet metal in approximately the form of a quarter sphere and is movable through a circular slot —20— into and out of the headlight case —1— and across the upper half of the stationary reflector —5— and glass plate —11— so that, when adjusted forwardly, it will intercept 30 the reflected rays from the upper half of the stationary reflector and reflect the light downwardly and rearwardly and for this purpose the movable reflector —6— is hinged at the center to its arc by hinged 35 pins —21— to brackets —22— which are rigidly secured by brazing or other fastening means to the inner faces of diametrically opposite sides of the case section —2— as shown more clearly in Fig. 4. These 40 hinged pins are secured to and preferably integral with a semi-circular spring wire bail —23— of slightly greater diameter than the concavo-convex portion of the stationary reflector —5— around the lower 45 part of which it is extended so as to normally lie flat against the marginal flange of said stationary reflector leaving sufficient clearance between the inner ends of the hinged pins —21— and adjacent portions of 50 the stationary reflector to allow the ends of the spring belt to be pressed against its own tension for withdrawing the hinged pins from engagement with the movable reflector to permit the removal of said reflector when necessary and also to facilitate the 55 assembling of said movable reflector in operative position without screws or bolts.

The movable reflector —6— is provided on its front or lower edge with a semi-circular marginal flange —24— forming a stop to limit its rearward swinging movement and also serving to cover the slot to prevent the entrance of dust and other foreign matter when the movable reflector is in its normal position or withdrawn into the case.

The rear portion of the movable reflector is also provided with an additional semi-anular flange —25— around the exterior thereof at substantially right angles to the plane of the flange —24— to form a stop 70 for engaging the inner face of the surrounding portion of the front of the case section —2— and thereby limiting the outward swinging movement of said movable section to the position shown in Figs. 2 and 3, thereby 75 additionally covering the slot —20— when the reflector —6— is adjusted for use.

As previously stated, the electric motor —7— is mounted within the case —1— and rigidly secured to the bracket —8— for supporting it free of the rear case section —3—. The armature shaft of the motor is provided with a worm —26— meshing with a worm gear —27— having a portion of its teeth cut away to form a recess —28— of 85 slightly greater circumferential length than that of the worm —26—, as shown more clearly in Fig. 5, the teeth of the worm and gear being substantially V-shape so as to afford a comparatively deep intermeshing 90 engagement. The object of this recess —28— is to prevent the operation of the gear more than one revolution at a time. The gear —27— is mounted upon the rear end of a forwardly extending shaft —29— 95 having its forward end provided with a pinion —30— meshing with a toothed segment —31— which is rigidly secured by rivets, brazing or otherwise to one side of the movable reflector —6— coaxial with its 100 pivotal pins —21— so that when the motor is operated similar rotary motion will be transmitted to the movable reflector.

Suitable means is provided for causing the teeth of the gear —27— to engage or 105 mesh with the worm —26— when the latter is registered with the recess —28— and for this purpose I have provided one face of the gear with a laterally projecting lug —32— against which bears one end of a 110 flat spring —33— having its opposite end secured to a stationary support —34— upon and within the rear case section —3—. That is the free end of the spring —33— lies in the path of movement of the lug —32— and 115 is arranged so that when the gear is rotating in one direction, as for example in the direction indicated by arrow X, Fig. 5, one end of the lug —32— will engage the spring and place it under tension at about 120 the same time that the recess —28— registers with the worm —26—, thereby causing the last tooth in advance of the recess to be pressed against the corresponding end of the worm ready to engage said worm 125 when the motor is reversed for reversing the operation of the gear and thereby reversing the operation of the movable section —6—.

The pinion —30— and its segment —31— are so proportioned as to cause the movable 130

reflector —6— to move through an arc of substantially 90° or from one extreme position to another at each revolution of the mutilated gear —27— first in one direction 5 and then in the opposite direction according to the direction of rotation of the motor armature which may be controlled in a manner well known to those skilled in that art. For example, in Fig. 5, the worm gear 10 —27— is shown as just having completed one revolution and stopped by the registration of the recess —28— with the worm —26— bringing one end of the lug —32— against the spring —33— for moving the 15 reflector —6— forwardly and downwardly to intercept the upper half of the rays of light from a stationary reflector and to simultaneously reflect such light downwardly and rearwardly on the pavement directly 20 in front of the machine some distance to the rear thereof which not only prevents the blinding of approaching horses and drivers of other vehicles and also pedestrians but also enables the downwardly and 25 rearwardly reflected rays of light to be used in making repairs upon or under the machine which could not be accomplished by any reflector located wholly within the case.

The wires, as —38—, leading from the 30 motor and also those leading from the lamp are brought out through one side of the rear case section —3— through an insulating bushing —39— and may be connected to any source of electric energy on the vehicle through the medium of a suitable reversing switch (not shown) but which will be located within easy reaching distance from the seat of the driver.

After moving the reflector —6— forwardly to its operative position, as previously described, it may be withdrawn into the case by the reverse action of the motor

which will cause a reverse movement of the worm gear —27—, thereby bringing the opposite end of the lug —32— into engagement with the opposite face of the spring to tension the latter in the opposite direction as soon as the recess —28— is again registered with the worm —26—, thereby causing the tooth at the opposite side of 50 the recess to rest against the worm ready for a repetition of the forward movement of the movable reflector —6— when desired.

What I claim is:

1. A headlight comprising a case, a stationary reflector within the case, a movable reflector operating through an opening in the front side of the case around the outside of the stationary reflector, and means 60 for operating the movable reflector.

2. A headlight comprising a case having a circular slot in its front side, a reflector movable in said slot and provided with stops coöoperating with the case for limiting its 65 inward and outward movement, an electric motor within the case, and means for transmitting motion from the motor to the reflector.

3. A headlight comprising a case having 70 an opening in its front end, a reflector movable in said opening into the case and beyond the front end thereof, an electric motor within the case, a worm on the armature shaft of the motor, a mutilated worm gear 75 meshing with said worm, and means for transmitting motion from the worm gear to the reflector.

In witness whereof I have hereunto set my hand this 3rd day of June, 1913.

FREDRICK F. MACLEAN.
